UNITED STATES PATENT OFFICE.

RUDOLPH HOFFMAN, OF KANKAKEE, ILLINOIS, ASSIGNOR TO SEARS, ROEBUCK AND COMPANY, OF CHICAGO, ILLINOIS, A CORPORATION OF NEW YORK.

OIL-BURNER.

1,254,226.

Specification of Letters Patent. Patented Jan. 22, 1918.

Application filed November 21, 1917. Serial No. 203,144.

To all whom it may concern:

Be it known that I, RUDOLPH HOFFMAN, a citizen of the United States, residing at Kankakee, in the county of Kankakee and State of Illinois, have invented certain new and useful Improvements in Oil-Burners, of which the following is a specification.

This invention relates to oil burners provided with tubular wicks, and particularly, 10 although not exclusively, to burners used in the type of stove known as oil heaters.

The invention has special reference to an air distributer or flame spreader for such a burner, the distributer being provided with 15 an annular flange by means of which the distributer is supported upon the wick. In order that there shall not be excessive vaporization of oil at the inner surface of the wick at the upper edge thereof, it is necessary that the wick flange and adjacent parts 20 shall not become excessively heated; and it is the object of the invention to prevent such excessive heating.

In the accompanying drawings, Figure 1 25 is a lower side view of an air distributer embodying the features of my invention. Fig. 2 is a transverse vertical sectional view taken in the plane of dotted line 2—2 of Fig. 1.

30 In the drawings, A denotes the air distributer and B the tubular wick. The distributer comprises a vertically extending sleeve 1, an annular outwardly extending imperforate flange 2 at the upper end of the 35 sleeve, an annular perforated flange 3 extending vertically from the outer edge of the flange 2, and a cap or spreader plate 4 attached to the upper edge of the flange 3. The parts 1, 2 and 3 may, if desired, be 40 formed from an integral piece of sheet metal. The cap 4 is imperforate save that it is provided with a central opening 5 to receive a rod (not shown) carrying the usual stop to limit upward movement of the air distributer 45 and hence of the wick.

Secured to and encircling the lower portion of the sleeve 1 is a sleeve 6 having an outwardly flaring annular flange 7. A wick flange 8 extends horizontally from the upper 50 edge of the flange 7. The parts 6, 7 and 8 may, if desired, be made from an integral piece of sheet metal. 9 is a frusto-conical or

upwardly tapering ring supported upon the inner portion of the wick flange 8 and extending thence upwardly and inwardly to 55 the sleeve 1. The ring 9 may be secured in place in any suitable manner, as by forming an annular bead 10 in the sleeve 1 just above the ring 9 whereby to hold the ring between the wick flange 8 and the bead 10. The 60 sleeve 1 is perforated all the way around, circumferentially of the sleeve, from a point adjacent to the lower portion of the flange 7 to the upper end of the sleeve. The flanges 7 and 9 are similarly perforated, although 65 preferably the perforations in the flange 7 are larger per unit of surface than the perforations in the sleeve 1. Preferably the perforations in the ring 9 are smaller per unit of surface than those in the sleeve 1. 70 The sleeve 1, the flange 7 and the ring 9 define or inclose an annular mixing chamber 75 extending around the sleeve 1 and communicating with the vapor-generating space between the inner surface of the wick 80 B and the distributer, and communicating also with the interior of the sleeve 1 and the space directly above the wick flange 8. A portion of the air current passing upwardly through the air distributer enters the 80 mixing chamber and passes out through the ring 9, thus serving to keep the wick flange 8 cool, preventing overheating of the flanges 7 and 8, and hence preventing excessive vaporization of the oil. 85

I claim as my invention:

An air distributer for an oil burner having, in combination, a vertical sleeve, an upwardly flaring annular flange surrounding and secured to the sleeve, an outwardly extending annular wick flange connected to the upper portion of the upwardly flaring flange, and a frusto-conical upwardly tapering ring extending from the inner portion of the wick flange to the sleeve, said sleeve, upwardly flaring flange and upwardly tapering ring being perforated and providing an annular mixing chamber arranged to discharge the mixture directly above the wick flange. 95

In testimony whereof, I have hereunto set my hand.

RUDOLPH HOFFMAN.
